UNITED STATES PATENT OFFICE.

JOHN K. RIDDLE, OF TOLEDO, OHIO, ASSIGNOR TO THE EDWARD N. RIDDLE COMPANY,
OF TOLEDO, OHIO, A CORPORATION OF OHIO.

LIGHTING FIXTURE.

Application filed October 23, 1924. Serial No. 745,297.

My invention relates to that class of lighting fixtures which are provided with arms to which are secured the electric switch sockets, into which is screwed the electric lamp bulb, and has for its object to construct an improvement on my co-pending application, Serial No. 618,215.

In the device shown in that application, there is no means shown whereby shades can be employed on the fixtures when desired. My present invention has for its object to permit the use of shades if desired and yet retain all the advantages of the device described in that application.

My means of accomplishing this object will be more readily understood by having reference to the accompanying drawings which are hereunto annexed and are a part of this specification, in which:

Fig. 1 is a top or plan view of a fragmentary portion of an arm of a lighting fixture.

Fig. 2 is a side view of the same, a portion of the arm and its outer end being broken away and shown in section to show the method of construction employed in attaining the advantageous results before set forth.

Similar references numerals refer to similar parts throughout the entire description.

As shown in the drawings, a fragmentary portion of the arm 1 only is shown as obviously the arm itself forms no part of my invention, it being apparent that any style or shape of arm can be employed. The outer end of the arm comprises an open ended cylindrical sleeve 2. In this sleeve is mounted the socket shell 3 of standard construction. When this shell is mounted in

the sleeve 2, it fits tightly for a portion of its length and is then swedged outwardly as at 4; this operates to hold the socket rigidly in position as is described in my prior application hereinbefore referred to. In this construction, however, I provide an annular space 5 which extends from the bottom 6 of the sleeve 2 up to a point 7 which is above the threaded portion 8. This space 5 permits the threaded portion 9 of the shade holder to enter into the annular space 5 so that the shade holder can be screwed upon the threads 8 formed on the socket shell.

It will be apparent from the foregoing description that in this manner I am enabled to mount a socket shell inside of the end of the arm holding the same securely in position and yet provide for the use of shades when desired, or for the use of ball lamp adapters when desired, both of which are desirable features in the manufacture of fixtures, as it permits the construction of a variety of styles or designs of fixtures without having to change the entire fixture.

Having described my invention, what I regard as new and desire to secure by Letters Patent of the United States is:

A lighting fixture arm having a vertical open ended cylinder at its outer end, a socket shell within said end, said shell being swedged to the inner wall of said cylinder, there being an annular space at the lower end of said cylinder intermediate the inner wall of the cylinder and the threaded portion of the shell whereby the threaded portion of a shade holder may be secured to the threads on the shell.

JOHN K. RIDDLE.
